Application August 26, 1944, Serial No. 551,408

19 Claims. (Cl. 60—52)

1

This invention relates to power presses and to fluid control circuits adapted for use therewith.

It is an object of the invention to provide an improved power press and associated fluid control circuit wherein the actuating fluid pressure, to the actuator or other operated device, may be varied and controlled in an improved manner.

Further objects of the invention are to provide in a power press structure and fluid control circuit of the type defined, an improved and simplified control arrangement wherein a single control member may be employed to control both the direction and the effective actuating pressure of the propelling fluid; and wherein an improved indicating arrangement is provided, in combination with the control means, for indicating the operating forces transmitted to the actuator.

A still further object of the invention is to provide an improved fluid control circuit for fluid operated power presses, specifically of the hydraulically actuated type, and for like material working apparatus.

Various other objects, advantages and features of the invention will be apparent from the following specification when taken in connection with the accompanying drawings wherein a preferred embodiment is set forth for purposes of illustration.

In the drawings, wherein like reference numerals refer to like parts throughout:

Fig. 1 is a general assembly view of a hydraulic power press and associated fluid control circuit constructed in accordance with and embodying the principles of the invention; parts of the casting structure being broken away to show the operating elements;

Fig. 2 is a side view of the hydraulic press structure shown in Fig. 1;

Figs. 3 and 4 are detail views, respectively, of two types of valve structures included in the fluid control circuit for the machine;

Fig. 5 is a detail view of the direction and pressure control valve unit, also forming a part of the fluid control circuit, said view being taken as indicated by the line 5—5 of Figs. 1 and 2;

Fig. 6 is a transverse sectional view through the direction and pressure control valve, taken as indicated by the line 6—6 of Fig. 5;

Fig. 7 is a longitudinal vertical section through the direction and pressure control valve, taken as indicated by the line 7—7 of Fig. 5;

Fig. 8 is a transverse sectional view through the direction and pressure control valve, taken

2

as indicated by the line 8—8 of Fig. 5, and more particularly illustrating the pressure control adjustment mechanism;

Figs. 9 and 10 are enlarged detail views of the pressure control valve shown in Fig. 8, the valve and associated adjustment mechanisms being illustrated respectively in two different positions of operation; and

Fig. 11 is a diagrammatic layout of the fluid control circuit.

In the drawings the fluid control circuit of the invention has been shown applied to a hydraulic bending or straightening press structure, as the invention in certain of its aspects is particularly adapted to a machine of this character. It is to be understood, however, that the invention in various of its aspects may also be adapted for effecting the actuation and control of other types of fluid actuated power press machines and structures.

Referring more particularly to the drawings, in Figs. 1 and 2 a power press is illustrated of the type, in the specific embodiment shown, which may be employed for bending or straightening work pieces. As shown, the machine comprises a frame or base 10 carrying a work bed 11. The bed 11 is arranged to carry a pair of work support pedestals 12 and 13 upon which may be mounted the work piece 14 to be bent or straightened. The machine base 10 also carries an actuator support bracket or pedestal 16 in the upper end of which is mounted a hydraulic actuator 17. As best shown in Fig. 11, the actuator comprises a vertically disposed cylinder 18 affixed to the support pedestal, and within which there is reciprocable a piston 19 having a rod portion 20 the lower end of which carries a pressure tool 21, adapted upon operation of the piston to be brought into engagement with the work piece 14 whereby to effect the bending or straightening operations.

As best shown in Fig. 1 one end of the machine base structure is adapted to form a housing for the parts comprising a fluid control circuit adapted to effect the actuation of the hydraulic actuator 17. The fluid control circuit, and its associated power and pumping mechanisms, comprise an electric motor 25 adapted to be energized from a suitable source of electric current supply, under control of a start button 26 and a stop button 27 disposed on a front portion of the machine base in a position convenient for manipulation by the operator. The motor 25, by means of a transmission mechanism consisting of driving and driven pulleys 30 and 31, connected by means

of a belt 32, effects the operation of a pumping unit generally indicated by the numeral 33. The pumping unit is disposed within a casing 35 enclosed within the machine base, the pumping unit comprising a gear pump portion 36 and a plunger pump portion 37, Figs. 1 and 11. As will be understood, and as will be hereinafter more specifically described, the gear and plunger pumps, under suitable control, are adapted to deliver the propelling fluid, preferably oil in the particular machine and control circuit illustrated, to the hydraulic actuator 17 to effect the operation of the reciprocable piston 19 and the associated tool 21.

The casing 35 carries a combined direction and pressure control valve 40, the details of which will be later described, for controlling the direction of movement of the piston 19, and also the pressure exerted thereon by the propelling fluid delivered from the pumps. The direction and pressure control valve includes an operating arm 41, fixed to a pivot shaft 42, and movable either clockwise or counterclockwise from the position illustrated in Fig. 1 between the limits determined by the stops 43 and 44. The valve operating arm is actuated by means of a link 45 pivotally connected at one end to the arm and at its other end to an arm 46 of a bell crank control lever 47 pivotally mounted upon the frame of the machine as indicated at 48. It will be seen that actuation of the manual control lever 47 from the full line position shown, either clockwise to the dotted line position 47a or counterclockwise to the dotted line position 47b, effects corresponding movement of the valve operating arm 41. While for illustrative purposes the operating lever 47 is shown in mid position or neutral position in Fig. 1, normally when the machine is not in operation it assumes its clockwise position as indicated at 47a, being normally shifted to and held in such position by means of a tension spring 49 connected at one end to the lever arm 46 and at its other end to a suitable anchorage on the machine frame or base.

As will presently be described, when the manual operating lever 47 is in its clockwise position 47a, and the pumps 36-37 are in operation, the piston 19 of the hydraulic actuator is caused to be returned or shifted in an upward direction to withdraw the forming tool 21 from the work piece. When the manual control lever is shifted to its counterclockwise position 47b the piston 19 is caused to be propelled downwardly to bring the tool 21 into engagement with the work piece, the pressure exerted by the propelling fluid upon the actuator piston being progressively increased as the control lever is shifted from its mid or neutral position to the counterclockwise position 47b. It will be seen that the single manually operable control lever 47 is thus operable to control the direction of travel of the actuator piston, and also operative to vary and control the pressure exerted by the hydraulic fluid upon the piston during its approach or downward movement, and after the forming tool has been brought into engagement with the work piece. The pressure may be varied between predetermined minimum and maximum limits, the actuating pressure being progressively increased as the control lever is shifted from its full line position, as indicated in Fig. 1, toward the counterclockwise position 47b. A pressure gauge 55, Figs. 1, 2 and 11, is arranged in the control circuit so as to indicate the pressure exerted by the hydraulic fluid upon the piston 19, during its

approach or downward movement. Preferably the gauge 55 is calibrated in terms of the total force in pounds, exerted by the working tool 21 upon the work piece.

The arrangement of the control circuit will be best understood by reference to Fig. 11. An oil reservoir 58 is formed within the casing 35 in the bottom portion thereof. The oil or propelling fluid is withdrawn from this reservoir by the gear pump 36 through a supply pipe 59. The outlet side of the gear pump is connected to a conduit 60 through which the oil may be delivered from the pump to any one or all of three conduits 61, 62, and 63 leading respectively to the plunger pump 37, a relief valve 64, and the direction valve portion 65 of the direction and pressure control valve structure 40. The fluid delivered to the relief valve 64 is returned when the valve is in open position to the reservoir 58 by means of drain lines or conduits 67 and 68. The fluid delivered to the plunger pump 37 through the supply line 61 is propelled by the pump through an outlet conduit 69 connecting with conduits 70 and 71 leading to the upper end of the hydraulic actuator cylinder 18. The pressure gauge 55 is interconnected with the pipe line 71. As will be understood, the gear pump 36 is preferably of the large volume, low pressure type, whereas the plunger pump 37 is of the low capacity, high pressure type. Accordingly, only a portion of the fluid delivered by the gear pump passes through the conduits 61 and 69, and through the plunger pump structure when the pumps are in operation. The gear and plunger pumps may be of any suitable construction, the details thereof forming no part of the present invention.

Fluid delivered by the conduit 63 to the reversing valve portion 65 of the direction and pressure control valve may be transmitted by the valve 40 either to a pair of interconnected conduits 75 and 76, or to a pair of interconnected conduits 77 and 78, depending upon the valve position. The conduits 75 and 77 are pilot pressure conduits for effecting the shifting of the valve member of a by-pass valve structure 80. As will be later described, the by-pass valve 80 is a two-position valve. In one position thereof it is arranged to connect a conduit 81 to a conduit 82 connecting with the return conduit 68 leading to the fluid reservoir. In the other position of the valve, fluid passage between the conduits 81 and 82 is broken.

When the reverse valve 65 is arranged to transmit fluid from the supply conduit 63 to the interconnected conduits 75 and 76, the oppositely disposed interconnected conduits 77 and 78 are connected through the valve to a drain line 85 leading to the fluid reservoir. Similarly when the valve is positioned to interconnect the supply conduit 63 with the conduits 77 and 78, the oppositely disposed conduits 75 and 76 are connected to drain.

When the reverse valve 65 is arranged to dispatch propelling fluid from the conduit 63 to the conduit 76, the fluid is delivered by said conduit 76 to a relief and check valve structure 88 through which the fluid is transmitted to a conduit 89 connecting with the conduits 70 and 71 leading to the upper end of the actuator cylinder 18. As will be later described, fluid may pass through the relief and check valve 88 in the direction indicated by the arrow, Fig. 11, but not in an opposite direction. Conversely, when the reverse valve 65 is positioned to direct fluid from the supply conduit 63 to the conduit 78, fluid is transmitted

thereby to a conduit 90 leading to the lower end of the actuator cylinder.

A conduit 91 connects with an intermediately disposed port in the actuator cylinder 18. This conduit leads to a relief and check valve structure 92 through which fluid may flow in the direction of the arrow but not in the opposite direction. Fluid passing through the valve 92 is delivered to a conduit 93 connecting with the conduits 90 and 78.

A conduit 95 connects with the conduit 71 and leads to the pressure control valve portion 96 of the direction and pressure control valve structure 40. As previously indicated, and as will later be more specifically described, this valve is adapted to control pressure conditions within the actuator during the approach or downward movement of the piston 19. When the valve 96 is opened, fluid delivered thereto through the conduit 95 is transmitted to a drain line 97 returning to the reservoir.

Before describing the manner of operation of the control circuit, the structural details of the by-pass valve 80, of the relief valves 64, 88 and 92, and of the direction and pressure control valve structure 40, will be described. The by-pass valve 80 is illustrated in Fig. 3. As will be seen, this valve structure comprises a shiftable valve member 100 longitudinally reciprocable within a bore of a valve casing 101 closed by end caps 102 and 103. When the valve member 100 is shifted to the right, as shown in Fig. 3, it will be seen that communication between the conduits 81 and 82, communicating respectively with valve ports 104 and 105, is cut off; whereas when the valve member is shifted to the left from the position shown, communication between the valve ports and conduits is established. The valve member 100 is shifted, as previously brought out, by fluid pressure directed thereto from one or the other of the conduits 75 and 77 communicating with the valve casing bore through the ports 106 and 107.

The relief valves 64, 88 and 92 may all be of generally similar construction, as indicated for example in Fig. 4. These valves comprise a casing 110 having a central chamber 111 closed by an end cap 112. A relief valve member 113 is reciprocable within the casing bore 114, said valve member having an axial passage 115 and a connecting transverse passage 116 adapted to communicate with the valve chamber 111 when the valve member is shifted to open position or upwardly, as seen in Fig. 4, against the action of a compression spring 117. As will be understood, the valve is opened against the action of the spring by fluid pressure within the bore 114. The force exerted by the compression spring tending to close the valve is adjustable by means of an adjustment screw 118 threaded into the end cap 112. When the valve is opened communication is established between the conduits 62 and 67 in the case of the valve 64, between the conduits 76 and 89 in the case of the valve 88, and between the conduits 91 and 93 in the case of the valve 92. Reverse flow from conduit 67 to conduit 62, or from conduit 89 to conduit 76, or from conduit 93 to conduit 91, is prevented, the valve thus constituting a relief and check valve structure. Adjustment of the set screw 118 will determine the relief pressure of the valve, in each instance. In the case of the valves 88 and 92 a very light spring and adjustment may be employed, the valves thus being essentially check valves, whereas in the case of valve 64 a heavier spring and adjustment may

be employed so as to provide a predetermined desired relief pressure for the gear pump outlet.

The direction and pressure control valve structure 40 is illustrated in Figs. 5 thru 10. It will be seen that the pivot shaft 42, to which the valve operating arm 41 is secured, is formed integrally with a valve member 125 oscillatable within a valve casing 126 formed as a part of the reverse valve portion 65 of the direction and pressure control valve structure. The valve member 125 is provided with a pair of slots 127 and 128 arranged to control communication between the conduits 63, 85, 75, 76, 77 and 78 communicating with the valve. When the valve member is in the position shown in Figs. 5, 6 and 7, corresponding to the full line control position in Fig. 1, the slots or passages 127 and 128 are inoperative to establish communication between the conduits. When the control lever 47 is in its control position 47a, the valve member 125 is moved counterclockwise as seen in Figs. 1 and 6 so that the passage 127 establishes communication between the supply conduit 63 and the conduits 77 and 78, interconnected within the valve by means of a casing port 130, Fig. 7; while simultaneously the conduits 75 and 76, interconnected by casing port 131, are placed in communication with the drain line 85 through the valve member slot or passage 128. When the control member 47 is moved to its position 47b, the valve is moved clockwise, as seen in Figs. 1 and 6, so that passage 128 connects the supply conduit 63 with conduits 75 and 76, whereas valve passage 127 connects the conduits 77 and 78 with the drain line 85. A pin 135, Fig. 5, fixed in the casing operates within an annular groove 136 formed in the valve member, so as to preclude the valve member from longitudinal movement.

An arm 140, Figs. 5, 7 and 8, is fixed to the reduced end portion 141 of the valve member 125, this arm being arranged to effect actuation of the pressure control valve portion 96 of the direction and pressure control valve structure. The pressure control valve 96 comprises a casing 142 within which is reciprocable a plunger member 143, the end portion 144 of which is adapted to be engaged by the end of the arm 140 when the reverse valve member 125 is moved to predetermined operating positions. A pin 145 limits the movement of the plunger to the left, as seen in Fig. 8.

The plunger member 143 engages a compression spring 146, Figs. 8, 9 and 10, the opposite end of which is arranged to engage a relief valve member 147 operable within the bore 148 of a bushing member 149. The bushing 149 is connected to the conduit 95 previously described, and is threaded into a sleeve 150 pinned to the casing 142 by means of a pin 151. The relief valve member 147 is provided with an axial passage 155 and a communicating radial passage 156 which in turn communicates with an angularly disposed annular channel 157 formed in the valve member. It will be seen that when pressure within the valve bore 148 builds up to a predetermined value, the relief valve is opened or shifted to the left, as seen in Figs. 8, 9 and 10, against the action of the compression spring 146 whereby to establish communication between conduit 95 and the drain conduit 97 communicating through the internal valve chamber 158.

The relief pressure, or pressure at which the relief valve 147 will open, is determined by the force exerted on the valve by the compression spring 146, which in turn is dependent upon the

position of the plunger member 143. When the direction valve member 125 is in its neutral or mid position as shown in Figs. 1, 6 and 8 the plunger 143 exerts only a predetermined minimum pressure upon the spring, determined by the position of the stop pin 145. As the control lever is moved to its control position 41a the arm 140 is moved clockwise, as seen in Fig. 8, to the position 140a away from the plunger, the position or setting of the plunger thus remaining unchanged. However, when the control lever is swung from its neutral or mid position to the operating position 41b, the arm 140 is moved counterclockwise from its Fig. 8 position to the position 140b, shifting the plunger 143 inwardly or to the right and progressively increasing the force exerted by the compression spring upon the relief valve. The plunger is shown in its minimum spring pressure position in Figs. 8 and 9, the relief valve being shown in closed position. In Fig. 10 the plunger is shown in position to exert a maximum force upon the spring, as when the control lever is in its position 41b. In Fig. 10 the relief valve 147 is shown in an open position.

Operation

Normally the control handle 47 is held in its position 41a by the tension spring 49, and the actuator piston 19 and associated working tool 21 are in their withdrawn or uppermost position. With the pumps 36 and 37 in operation, being driven by the motor 25, fluid is drawn from the reservoir 58 through the supply conduit 59 by the gear pump 36 and delivered to the pump outlet conduit 60. Part of the fluid from the conduit 60 passes through the supply conduit 61 to the plunger pump 37 and is delivered thereby to the conduits 69 and 70. The remainder of the fluid from the conduit 60 passes through the conduit 62 and through relief valve 64 to the drain conduits 67 and 68 to the reservoir. Pressure is maintained on the conduit 63 at the setting of the relief valve 64, which in an illustrative embodiment may be on the order of 75#/sq. in. This pressure is transmitted through the reverse valve 65 to the conduits 71 and 78 (the control lever 47 being in its position 41a). The pressure in conduit 71 ensures that the by-pass valve 80 will be maintained in its leftward position as seen in Fig. 3, establishing communication between the conduits 81 and 82. The pressure in the conduit 78 is transmitted to the conduit 90 whereby to maintain the actuator piston 19 in its uppermost position. The fluid delivered by the plunger pump through the conduits 69 and 70 is returned to the reservoir at substantially no pressure through the conduits 81 and 82.

When it is desired to bring the working tool 21 downwardly into engagement with the work, the control handle 47 is swung counterclockwise, as seen in Fig. 1, from the position 41a to and slightly past the full line mid position. As the control handle is moved past its mid or neutral position the relief valve 64 closes and the bulk of the fluid from the conduit 60 is delivered through the conduit 63 and through the reverse valve 65 to the conduits 75 and 76. The pressure fluid delivered to the conduit 75 shifts the by-pass valve 80 to the right or to closed position. The pressure fluid delivered to the conduit 76 passes through the check valve 88 (at a pressure drop or relief spring setting sufficient only to ensure the maintenance of sufficient pressure within the pilot conduit 75 to effect proper shifting of the by-pass valve 80) and through the conduits 89, 70 and 71 to the

upper end of the hydraulic actuator 18. The fluid delivered to conduits 70 and 71 from the conduit 89 is supplemented by the fluid from the plunger pump, received through conduits 61 and 69.

As the piston 19 moves downwardly the return fluid from the actuator passes through conduits 90 and 78, and through the reverse valve 65 to the drain line 85 and to the reservoir. The valve pilot line 77, being connected to drain, permits the shifting of the valve 80, as stated.

During the downward approach movement or traverse of the piston 19 the maximum pressure which can be exerted on the piston is determined by the setting of the relief valve 96 of the direction and pressure control valve structure, inasmuch as this valve is directly connected to the actuator supply line 71 by means of the conduit 95. The arm 140 having been moved only slightly counterclockwise from the position shown in Fig. 8, the spring 146 is only slightly compressed and accordingly the relief pressure of the valve 86 at this time is relatively low, sufficient only to ensure downward traverse of the actuator piston. During downward traverse of the actuator piston, the relief setting of the valve 96 may for example be on the order of 10#/sq. in. although, as will be understood, this setting may be varied in accordance with the requirements of the particular installation.

As the forming tool 21 engages the work piece, and movement of the piston 19 is arrested, the relief valve 96 (having a lower pressure setting than the relief valve 64) opens to divert the fluid from the actuator supply line 71. As it may now be desired to increase the pressure engagement between the tool and the work, the control handle 47 may be progressively advanced toward its position 41b, whereby to progressively increase the propelling pressure of the fluid in the actuator. As the pressure setting of the valve 96 is increased above the setting of the relief valve 64, the latter opens to divert the bulk delivery of fluid from the gear pump to the drain lines 67 and 68. However, the plunger pump 37 continues to deliver fluid through the conduits 69, 70 and 71 to the actuator, at a pressure controlled by the relief or pressure control valve 96. Reverse flow of the plunger pump fluid through the conduits 89 and 76 is prevented by the check valve 88. The control handle 47 may be progressively shifted toward its position 41b to progressively increase the propelling force of the fluid on the actuator to the maximum limits of the circuit which may be on the order of several thousand pounds per square inch, depending upon the requirements of the installation. The pressure gauge 55, calibrated in terms of total force exerted by the tool on the work, continuously indicates pressure and working conditions.

To protect the lower end cap 18a of the actuator from the high pressures possible in the system during downward traverse of the piston, means is provided for preventing the high pressure impact of the piston 19 against the end cap 18a in the event the work piece should break or not be present to furnish resistance to the working tool. When the piston 19 reaches its extreme lowered position as indicated in Fig. 11, it uncovers the cylinder port connected to the conduit 91. Under these conditions fluid delivered to the actuator from the conduit 71 is by-passed through the conduit 91, the relief valve 92 and the conduits 93 and 78 to the reservoir at the pressure setting of the relief valve 92.

To return the actuator piston to uppermost position the control handle 47 is shifted to its position 47a. As the control lever is shifted the relief valve 64 closes (assuming the actuator piston encounters no unusual resistance) and the bulk of the fluid from the gear pump 36 is delivered through conduits 60 and 63, and through the reverse valve 65, to conduits 77 and 78. The pressure fluid in pilot conduit 77 shifts the bypass valve 80 leftward or to open position. The fluid in conduit 78 is delivered through conduit 98 to the lower end of the actuator cylinder to propel the piston 19 upwardly. Reverse flow through conduits 93 and 91 is prevented by the check valve 92. The return fluid from the actuator passes through conduits 71 and 81 and through the by-pass valve 80, to drain conduits 82 and 68. The pilot valve conduit 75 is connected by the reverse valve 65 to the drain line 85, so as to permit the shifting of the by-pass valve 80. During the upward travel of the actuator piston, the fluid delivered by the plunger pump 37 passes through conduits 61 and 69 to conduit 81, and thence to drain through the by-pass valve 80 and the drain lines 82 and 68. Accordingly, during upward traverse of the piston the fluid from the plunger pump is not used for propelling purposes. However the upward traverse rate of the piston, in the particular embodiment shown, is none the less substantially double the downward traverse rate, due to the differential areas on the opposite faces of the piston because of the piston rod 20.

When the piston reaches the upper limit of its travel the relief valve 64 opens, the piston being maintained in its uppermost position by the pressure setting of the valve 64, and conditions being established as initially described.

It will thus be seen that a control circuit for the hydraulic actuator is provided wherein the desired movements of and pressure conditions upon the piston at all times are controlled in a desired manner; and wherein the single control lever 47 is employed both to control the direction of actuator travel and also accurately and variably to control the pressure engagement between the forming tool and the work piece. The magnitude of the pressure engagement with the work is continuously indicated by the gauge 55.

It is obvious that various changes may be made in the specific embodiment set forth without departing from the spirit of the invention. Accordingly the invention is not to be limited to the specific embodiment shown and described, but only as indicated in the following claims.

The invention is hereby claimed as follows:

1. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections including a reversing valve and an adjustable pressure control valve for transmitting propelling fluid from the propelling means to the actuator, and a single control member associated with said circuit connections operable upon the reversing valve for controlling the direction of travel of said actuator and upon the pressure control valve for variably controlling the pressure of the propelling fluid transmitted thereto, said control member being shiftable to a first position to dispatch fluid to the actuator in one direction, to a second position to dispatch fluid to the actuator in the opposite direction, and to

5 a third position for variably adjusting the pressure of the propelling fluid, and means for biasing said control member toward and for normally maintaining said control member in said first position.

2. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections including a direction valve and a pressure control valve for transmitting propelling fluid from the propelling means to the actuator, and a single control member associated with said circuit connections to shift said direction valve for controlling the direction of travel of said actuator and to shift the pressure control valve for variably controlling the pressure of the propelling fluid transmitted thereto, said control member being shiftable to a first position to dispatch fluid to the actuator in one direction, to a second position in a given direction to dispatch fluid to the actuator in the opposite direction at a predetermined constant minimum pressure, and to a third position in the same direction for progressively increasing the pressure of the propelling fluid.

3. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections including a direction valve and a pressure control valve for transmitting propelling fluid from the propelling means to the actuator, and a single reciprocable control member associated with said circuit connections to shift said direction valve for controlling the direction of travel of said actuator and to shift the pressure control valve for variably controlling the pressure of the propelling fluid transmitted thereto, said control member being shiftable in one direction to a first position to dispatch fluid in one direction to the actuator, said control member being shiftable in the opposite direction to a second position to dispatch fluid in the opposite direction to the actuator at a predetermined minimum pressure, and said control member being further operable in said latter direction to a third position to variably increase the pressure of the propelling fluid while maintaining operative connections for the fluid between the propelling means and said actuator in said opposite direction, and means for biasing said control member toward and for normally maintaining said control member in said first position.

4. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections for transmitting propelling fluid from the propelling means to the actuator, said circuit connections including a direction valve for controlling the direction of fluid flow to the actuator and a pair of pressure control valves respectively operable to control the propelling pressure of the propelling fluid delivered to the actuator in its opposite directions

of travel, and a common controlling member for said direction valve and for adjusting the control pressure of at least one of said pressure control valves.

5. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections for transmitting propelling fluid from the propelling means to the actuator, said circuit connections including a rotary direction valve for controlling the direction of fluid flow to the actuator and a pressure adjustable control valve for controlling the propelling pressure of the propelling fluid delivered to the actuator, and a common controlling member for said direction valve and for said pressure control valve, said controlling member being shiftable along a given path of travel between predetermined limits to effect the operative reversal of said direction valve, and being shiftable between additional limits along the same path of travel to effect the variable adjustment of said pressure control valve while maintaining the direction valve in one of its operative positions.

6. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections for transmitting propelling fluid from the propelling means to the actuator, said circuit connections including a direction valve for controlling the direction of fluid flow to the actuator and a spring closed pressure adjustable control valve for controlling the propelling pressure of the propelling fluid delivered to the actuator, and a common controlling member for shifting said direction valve and for adjusting the control pressure of said pressure control valve, said controlling member being positively connected to the direction valve and having a lost motion connection with said pressure control valve.

7. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections for transmitting propelling fluid from the propelling means to the actuator, said circuit connections including a rotary direction valve for controlling the direction of fluid flow to the actuator, and a spring closed reciprocable pressure adjustable control valve for controlling the propelling pressure of the propelling fluid delivered to the actuator, and a common controlling member reciprocably operable to rotate said direction valve and to control the opening pressure of said pressure control valve against the action of said spring.

8. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections including a reversing valve and

a pressure adjustable control valve for transmitting propelling fluid from the propelling means to the actuator, a single control member associated with said circuit connections operable between predetermined limits to shift the reversing valve for controlling the direction of travel of said actuator and between different limits to adjust the pressure control valve for variably controlling the pressure of the propelling fluid transmitted thereto, pressure gauging means for indicating the pressure of the propelling fluid in the propelling end of the actuator, and means for biasing said control member toward and for maintaining it in a predetermined position.

9. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections for transmitting propelling fluid from the propelling means to the actuator, said circuit connections including a propelling line and a direction valve for controlling the direction of fluid flow to the actuator, and a pressure control valve for controlling the fluid pressure in the propelling line to the actuator during travel of the actuator in one direction, common controlling means for said direction valve and for said pressure control valve, and a valve for controlling the pressure in said propelling line upon reversal of said actuator.

10. A power press structure comprising support means for a press tool, support means for a work piece to be operated upon by said tool, and means for shifting said support means relative to each other to selectively engage and disengage the tool and work piece comprising a fluid operated actuator, propelling means for fluid, said propelling means comprising a relatively large volume low pressure pump and a relatively low volume high pressure pump, circuit connections for transmitting propelling fluid from the propelling means to the actuator, said circuit connections including a direction valve for controlling the direction of fluid flow from both pumps to the actuator and a pressure control valve for controlling the propelling pressure of the propelling fluid delivered to the actuator from one of said pumps, and a common controlling member for said direction valve and for said pressure control valve.

11. A power press structure comprising support means for a press tool, support means for a work piece to be operated upon by said tool, and means for shifting said support means relative to each other to selectively engage and disengage the tool and work piece comprising a fluid operated actuator, propelling means for fluid, said propelling means comprising a relatively large volume low pressure pump and a relatively low volume high pressure pump, circuit connections for transmitting propelling fluid from the propelling means to the actuator, said circuit connections including a direction valve for controlling the direction of fluid flow to the actuator, and a variable pressure control valve for controlling the maximum propelling pressure of the high pressure pump, control handle operating means for said direction valve and for said variable pressure control valve, and a relief valve for controlling the maximum pressure delivery of said low pressure pump.

12. A power press structure comprising sup-

port means for a press tool, support means for a work piece to be operated upon by said tool, and means for shifting said support means relative to each other to selectively engage and disengage the tool and work piece comprising a fluid operated actuator, propelling means for fluid, said propelling means comprising a relatively large volume low pressure pump and a relatively low volume high pressure pump, circuit connections for transmitting propelling fluid from the propelling means to the actuator, said circuit connections including a direction valve for controlling the direction of fluid flow to the actuator, and a variable pressure control valve for controlling the maximum propelling pressure of the high pressure pump during travel of the actuator in one direction, control handle operating means for said direction valve and for said variable pressure control valve, and a relief valve for controlling the maximum pressure delivery of said low pressure pump during travel of the actuator in said one direction and for controlling the maximum pressure in the circuit during travel of the actuator in the opposite direction.

13. A power press structure comprising support means for a press tool, support means for a work piece to be operated upon by said tool, and means for shifting said support means relative to each other to selectively engage and disengage the tool and work piece comprising a fluid operated actuator, propelling means for fluid, circuit connections for transmitting propelling fluid from the propelling means to the actuator, said circuit connections including a direction valve for controlling the direction of fluid flow to the actuator and a pressure control valve for controlling the propelling pressure of the propelling fluid delivered to the actuator during travel thereof in one direction, a common controlling member for said direction valve and for said pressure control valve, and a relief port in said actuator for decreasing the fluid propelling pressure when the actuator reaches a predetermined position during its movement in said one direction.

14. A fluid control circuit for material working apparatus comprising a fluid operated actuator, propelling means for fluid, said propelling means comprising a relatively large volume low pressure pump and a relatively low volume high pressure pump, circuit connections for transmitting propelling fluid from the propelling means to the actuator, said circuit connections including a direction valve for controlling the direction of fluid flow to the actuator, a variable pressure control valve for controlling the maximum propelling pressure of the high pressure pump during travel of the actuator in one direction, common control means for the direction valve and the pressure control valve, a by-pass valve open upon reversal of the actuator for disabling the pressure control of said pressure control valve, and a relief valve for controlling the maximum pressure in the circuit during movement of the actuator in the opposite direction.

15. A power press structure comprising support means for a press tool, support means for a work piece to be operated upon by said tool, and means for shifting said support means relative to each other to selectively engage and disengage the tool and work piece comprising a fluid operated actuator, propelling means for fluid, said propelling means comprising a relatively large volume low pressure pump and a relatively low volume high pressure pump, circuit connections for transmitting propelling fluid from the prop-

elling means to the actuator, said circuit connections including a direction valve for controlling the direction of fluid flow from both pumps to the actuator, and a variable pressure control valve for controlling the maximum propelling pressure of the high pressure pump, a control handle operable between first and second positions for effecting the operation of the direction valve and to a third position for variably actuating the pressure control valve, and a relief valve for controlling the maximum pressure delivery of said low pressure pump.

16. A power press structure comprising support means for a press tool, support means for a work piece to be operated upon by said tool, and means for shifting said support means relative to each other to selectively engage and disengage the tool and work piece comprising a fluid operated actuator, propelling means for fluid, said propelling means comprising a relatively large volume of low pressure pump and a relatively low volume high pressure pump, circuit connections for transmitting propelling fluid from the propelling means to the actuator, said circuit connections including a direction valve for controlling the direction of fluid flow to the actuator, a by-pass valve for relieving pressure from the high pressure pump during movement of the actuator in one direction, and a variable pressure control valve for controlling the maximum propelling pressure of the high pressure pump during movement of the actuator in the opposite direction, and common control means for effecting the actuation of said direction valve, said by-pass valve, and said variable pressure control valve, and a relief valve for controlling the maximum pressure delivery of said low pressure pump.

17. A power press structure comprising support means for a press tool, support means for a work piece to be operated upon by said tool, and means for shifting said support means relative to each other to selectively engage and disengage the tool and work piece comprising a fluid circuit having a fluid operated actuator, propelling means for fluid comprising a plurality of pumps, and circuit connections including a reversing valve for transmitting propelling fluid from the propelling means to the actuator, said fluid circuit including means for propelling the actuator from both pumps at a predetermined faster rate of travel so long as the actuator encounters less than a predetermined resistance to movement, a relief valve automatically operable as the actuator encounters a predetermined load resistance for diverting fluid from one pump to propel the actuator at a predetermined slower rate of travel from the other pump, a relief valve for controlling the pressure delivery of said other pump, and common control means for said reversing valve and for said last named relief valve.

18. A power press structure comprising support means for a press tool, support means for a work piece to be operated upon by said tool, and means for shifting said support means relative to each other to selectively engage and disengage the tool and work piece comprising a fluid circuit having a fluid operated actuator, propelling means for fluid, and circuit connections including a direction valve for transmitting propelling fluid from the propelling means to the actuator, said fluid circuit including means for propelling the actuator at a predetermined faster rate of travel so long as the actuator encounters less than a predetermined resistance to movement, a relief valve automatically operable as the

actuator encounters a predetermined load resistance for diverting a portion of the fluid from the propelling means to propel the actuator at a predetermined slower rate of travel, means for variably adjusting the maximum propelling pressure of the actuator during its slower travel rate, and a common control device for actuating said last named means and said direction valve.

19. A power press structure comprising support means for a press tool, support means for a work piece to be operated upon by said tool, and means for shifting said support means relative to each other to selectively engage and disengage the tool and work piece comprising a fluid operated actuator, propelling means for fluid circuit connections for transmitting propelling fluid from the propelling means to the actuator, said circuit connections including a reversing valve, a by-pass valve for by-passing fluid from the propelling means when the actuator is propelled in one direction, and an adjustable pressure control valve for variably controlling the pressure in the actuator when it is propelled in the opposite direction, and a common control member for effecting the actuation of said reversing valve and of said pressure control valve.

GUSTAF J. PETERSON.
